UNITED STATES PATENT OFFICE.

OLIVIA W. TUCKER, OF BROOKLYN, NEW YORK.

LAMP-SHADE.

1,214,847.

Specification of Letters Patent.

Patented Feb. 6, 1917.

Application filed September 16, 1916. Serial No. 120,502.

To all whom it may concern:

Be it known that I, OLIVIA W. TUCKER, a citizen of the United States of America, residing at Brooklyn, Kings county, New York, have invented a new and useful Lamp-Shade, of which the following is a specification.

My invention relates to a new and improved lamp shade. The object of the invention is to provide an ornamental fabric shade which may be readily attached to an ordinary fixture, the construction being such that it is adaptable as to size. The shade, in its preferred form, is also adjustable, whereby a single shade may be applied to a wide variety of sizes of lamp fixtures.

In the drawings:

Figure 1 is a perspective view of the shade open at one side.

Fig. 2 is a sectional view.

In the drawings I have shown my invention as applied to an overhead lighting fixture. My shade in the particular form shown comprises a band 1, from which depends what I may term an upper skirt 2. The lower edge of this upper skirt is reinforced by a strip or band 3 from which depends what I may term a lower skirt 4. The lower edge of the lower skirt is reinforced by a strip or band 5. 6 is a fringe which may depend from the band 3. 7 is a fringe which may depend from the band 5. The upper skirt 2 is preferably made from silk taken in so as to form small pleats. The upper edge of this skirt 2 is formed with a pocket around the same within which is located the band 1. The band 3 is located within a pocket or at the lower edge of the upper skirt 2. The band 5 is located within a pocket formed at the lower edge of the lower skirt 4. In the particular form shown, the band 3, when the shade is in its final form and in position, is larger than the bands 1 and 5. These dimensions may, of course, be varied to suit different conditions and tastes.

The strips or bands 3 and 5 should preferably be formed of a suitable material which will operate as a stay, for example, the well known material "featherbone" may be successfully employed. The band 1 is preferably of elastic material so that the shade may neatly fit on fixtures of different sizes.

In the preferred form, the ends of the respective bands are separable and adjustable

so that it will be possible for the owner to modify the appearance of the shade by increasing or decreasing the diameter of the respective bands. To that end I may provide at the ends of the respective bands, any suitable fastening devices which will permit the purchaser to effect the aforesaid adjustment with the greatest ease. In the particular form shown in the drawings, I have provided one end of each band with a ball fastening 8 and I have provided the other end of each band with a series of socket fastenings 9—9 to receive said balls. When the ends of the respective bands have been connected so as to secure the desired adjustment, the material on the bands back of the then exposed ends may be slid forwardly so as to completely cover and hide the connected ends of the respective bands. This gives a continuous effect to the upper and lower skirt portions and to the fringes entirely around the fixture.

By constructing the shade in this latter form the said device may be made and sold in the opened up form so that the purchaser may use his or her taste in connecting up the ends of the shade by overlapping the ends of the respective bands more or less as desired for securing the particular effect desired. 10 is an ornamental band or belt of material shirred upon an elastic core which may be applied to cover the upper band 1, if desired, and which in some instances, may add to the attractiveness of the article. It will be understood, of course, that sufficient fullness is given to the material so that it will have a shirred effect upon the respective bands, although this is not essential in all cases.

While I have shown ornamental fringes, obviously the same are not essential, although in many cases preferable.

This fabric shade may be applied with great success to fixtures of the bowl shade type where indirect light is sought and without in any substantial way interfering with the same. When used in connection with a table light of this character, the lower skirt 4 serves to shade the eyes of those around the table, while a more intense light is permitted to pass through the lower central open part of the shade. The open upper part of the shade permits the direct rays from the lamps proper to go upwardly toward the ceiling in the intended manner.

In many other respects, the aforesaid con-

struction has advantages that will plainly appear to anyone familiar with this art.

What I claim is:

1. A lamp shade comprising an upper and lower flexible skirt portion, a reinforcing band between the same, an expandible and contractible band at the upper edge of the upper skirt, and a reinforcing band at the lower edge of the lower skirt.
2. A lamp shade comprising an upper and lower flexible skirt portion, a reinforcing band between the same, an expandible and contractible band at the upper edge of the upper skirt, and a reinforcing band at the lower edge of the lower skirt, the upper band being elastic.
3. A lamp shade comprising an upper and lower flexible skirt portion, a reinforcing band between the same, an expandible and contractible band at the upper edge of the

upper skirt, and a reinforcing band at the lower edge of the lower skirt, one of said bands being adjustable as to length.

4. A lamp shade comprising an upper and lower flexible skirt portion, a reinforcing band between the same, an expandible and contractible band at the upper edge of the upper skirt, and a reinforcing band at the lower edge of the lower skirt, all of said bands being adjustable as to length.

5. In a lamp shade of the character described, a plurality of bands, a fabric skirt-like connection between said bands with pockets therein within which said bands are located, means for connecting the ends of said bands, said pockets being arranged to permit the fabric to be slid over said connections to hide the same and to form a continuous shade.

OLIVIA W. TUCKER.
